No. 797,193.

PATENTED AUG. 15, 1905.

T. H. GILBERT.
CAR JOURNAL BOX.
APPLICATION FILED JUNE 10, 1905.

UNITED STATES PATENT OFFICE.

TRUMAN H. GILBERT, OF BUFFALO, NEW YORK, ASSIGNOR OF ONE-HALF
TO JOHN C. BRADLEY, OF BUFFALO, NEW YORK.

CAR JOURNAL-BOX.

No. 797,193.

Specification of Letters Patent.

Patented Aug. 15, 1905.

Application filed June 10, 1905. Serial No. 264,670.

To all whom it may concern:

Be it known that I, TRUMAN H. GILBERT, a citizen of the United States, residing at Buffalo, in the county of Erie and State of New York, have invented a new and useful Improvement in Car Journal-Boxes, of which the following is a specification.

This invention relates to car journal-boxes of the Master Car-Builders' type which have hinged lids for the filling-openings, and more particularly to means for closing the lid and holding it firmly in closed position.

The objects of the invention are to provide a spring-closing device for journal-box lids of simple, durable, and inexpensive construction, such that it will hold the lid open temporarily, but will allow it to close by the action of gravity if left open and will firmly hold the lid closed, so as to prevent the entrance of dust, water, or other foreign matter into the box, and to construct the closing device so that it will effectually pack the lid-hinge to prevent the entrance of dust, water, or other foreign matter into the box at the hinged end of the lid.

In the accompanying drawings, Figure 1 is a fragmentary longitudinal vertical section of a journal-box provided with a lid-closing device embodying the invention. Fig. 2 is a similar view thereof, showing a different position of the lid. Fig. 3 is a fragmentary transverse sectional elevation thereof in line 3-3, Fig. 1. Fig. 4 is a fragmentary plan view thereof.

Like letters of reference refer to like parts in the several figures.

A represents the outer end portion of a car journal-box of the Master Car-Builders' construction, having an inclined end face provided with a filling-opening *a*, and B represents the lid for the filling-opening, hinged as usual at its upper end to the top of the box. Preferably the box has an upright projection or ridge C, which extends transversely across the top from side to side of the box at its outer end, and this ridge is provided at its opposite ends—that is, at the opposite sides of the box—with perforated hinge ears or lugs *c*, through which and a perforated hinge-lug *d* on the lid passes the usual hinge pin or bolt *d'*. The lid-lug *d* extends from one to the other of the box-lugs *c* and is preferably about equal in length to the width of the fill-

ing-opening. The lid-lug *d* has an outer or upper face *d*², which is rounded or curved substantially concentrically with the hinge-pin, and an under flat face *d*³, which joins the curved outer face in an abrupt longitudinal angle or corner *d*⁴. The ridge C on the box has an elongated vertical spring pocket or chamber E, in which is confined a horizontal vertically-movable closing and packing bar F, which is supported on one or more springs *f*, located in the chamber E beneath the bar F. Two coil-springs are preferably employed and are held in upright position by studs *f'* on the bar and bottom of the chamber, which enter the ends of the springs. The closing and packing bar, which is equal in length to the lid-lug *d*, is pressed upwardly by the springs *f* against said lid-lug and bears against the corner *d*⁴ thereof when the lid is closed, as shown in Fig. 1, and against the curved outer face thereof when the lid is open, as shown in Fig. 2. The location of the corner *d*⁴ of the lid-lug is such that the upward pressure of the closing-bar thereon tends to swing the lid downwardly and inwardly, thereby holding it firmly and securely against the rim of the filling-opening and effecting a tight closure of the box. When the lid is raised, the closing-bar is pressed downwardly by the corner *d*⁴ on the lid-lug and the springs *f* are compressed somewhat. The pressure of the closing-bar on the rounded face of the lid-lug when the lid is open is sufficient to hold the lid open so long as no force is exerted on the lid to close it. If the lid should be left open, however, the jarring of the box when the car is in motion, aided by the action of gravity, will cause the lid to lower gradually until the corner *d*⁴ of the lid-lug bears against the closing-bar, when the pressure of the latter will throw the lid closed and hold it firmly in the closed position. As the closing-bar is pressed against the lid-lug at all times by its springs and is coextensive in length with said lid-lug, it serves to close the space between the lid-lug and the box and effectually prevents the entrance of dust, water, or other foreign matter into the box at this point. The lid is preferably provided with side flanges G, which embrace the sides of the outer end of the box and its hinge-lugs to further guard against the entrance of dust, &c., into the box.

The closing device constructed as described

is exceedingly simple, and the parts can be assembled quickly and with little labor. There are no projections on the lid, which are always objectionable, as they are liable to be struck and broken. The device does not project into and occupy space within the box, and it occupies but little, if any, more space than the hinge-lugs on the standard journal-boxes.

I claim as my invention—

1. The combination of a journal-box, a lid hinged to the box by connected integral lugs on the top of the box and upper end of the lid, a spring-pressed bar located in a chamber on the box beneath the lid-lug and bearing upwardly against said lug, said lug having a face curved concentrically with the axis of the hinge and terminating in a corner against which said spring-pressed bar bears upwardly to close the lid, substantially as set forth.

2. The combination of a journal-box, a lid hinged to the box by connected hinge-lugs on the box and lid, a spring-pressed bar on the box which bears against the lid-lug to close the lid, said bar bearing against the lid-lug for substantially its full length and closing

the space between said lid-lug and the box, substantially as set forth.

3. The combination of a journal-box having separated hinge-lugs and a spring-chamber between said lugs, a lid having a hinge-lug connected to said lugs on the box and closing the open side of said spring-chamber, and a spring-pressed bar located in said spring-chamber and bearing against said lid-lug to hold the lid closed, substantially as set forth.

4. The combination of a journal-box having separated hinge-lugs at its top and an open-topped spring-chamber between said lugs, a lid having a hinge-lug connected to said lugs on the box and overhanging said spring-chamber, a vertically-movable bar in said spring-chamber bearing against said lid-lug, and one or more springs in said chamber beneath said bar for pressing the latter upwardly against said lid-lug, substantially as set forth.

Witness my hand this 8th day of June, 1905.

TRUMAN H. GILBERT.
